(57) **CLAIM**

The ornamental design for a bug zapper racket, as shown and described.

DESCRIPTION

FIG. 1 is a front view of the bug zapper racket;
FIG. 2 is a rear view of the bug zapper racket of FIG. 1;
FIG. 3 is a left side view of the bug zapper racket of FIG. 1;
FIG. 4 is a right side view of the bug zapper racket of FIG. 1;
FIG. 5 is a top view of the bug zapper racket of FIG. 1; and,
FIG. 6 is a bottom side view of the bug zapper racket of FIG. 1.

The elements delineated in dashed lines form no part of the claimed design of the bug zapper racket.
